(57) **CLAIM**

The ornamental design for a tie, as shown.

DESCRIPTION

The claimed tie is an ornamental tie to be worn with casual clothes.

FIG. 1 is a front view of a tie, as it would be worn, with belt loops and pocket showing my new design;

FIG. 2 is a full length frontal view thereof; and,

FIG. 3 detailed and enlarged so as to be easily and clearly seen view of the front ornamental aspect view.
